APPARATUS FOR STRETCHING SHEET MATERIAL

Arthur G. Borntraeger, Akron, Ohio, assignor to
Nicholas Allstatter and to said Borntraeger

Application October 1, 1934, Serial No. 746,344

8 Claims. (Cl. 45—24)

This invention relates to improvements in apparatus for stretching sheet material and while adapted for use generally wherever it may be advantageously employed, it is particularly intended for application to curtain stretching frames, in which connection it is illustrated in the drawings and hereinafter specifically described.

Objects of the invention are to provide a frame 10 of simple, durable construction which may be quickly and conveniently adjusted and efficiently used to stretch or hold in a normal condition, curtains or other flat, flexible articles of different sizes.

Other objects are to provide a curtain stretching frame having a horizontally movable, vertical curtain engaging bar and a vertically movable, horizontal curtain engaging bar mounted with each end of each bar secured to an endless, flexible belt arranged to maintain said bars at right angles to each other and at right angles to the adjacent side frame member and to thereby provide a frame which may be quickly adjusted to receive rectangular curtains of any reasonable width and length and which will uniformly hold the same in rectangular form during the stretching operation.

An additional object is to provide a curtain stretcher of the type above indicated which is composed of separable parts adapted to be quickly and conveniently assembled to form a strong, rigid structure and which can be quickly taken apart for shipment or storage.

An illustrative embodiment of the invention is shown in the drawings and hereinafter specifically described, it being understood that the invention is not limited to the exact form shown and that changes and modifications may be made which come within the spirit of the invention as set forth in the appended claims.

In the drawings:—

Figure 1 is a front, elevational view of a curtain stretching frame constructed in accordance with this invention.

Figure 2 is a rear elevational view of same, Figure 3 is a vertical, sectional view taken as indicated by the lines 3—3 of Figure 2,

Figure 4 is a horizontal, sectional view taken as indicated by the lines 4—4 of Figure 2.

Figure 5 is a diagrammatic view illustrating a modified form of mounting the movable curtain engaging bars.

Figure 6 is a sectional view taken as indicated by the lines 6—6 of Figure 1.

Proceeding now to a detailed description of the

invention with reference to the particular adaptation of the invention disclosed in the drawings, the numeral 10 denotes the lower rail and the numeral 11 the upper rail of a fixed frame and the numerals 12 and 13 denote the side rails 5 thereof. The bottom and top rails 10 and 11 and the side rails 12 and 13 meet in a butt joint at the corners of the frame and are held in assembled relation by the corner members 14, one of which is positioned at each corner of the 10 frame. The corner member 14 is L-shaped and is composed of sheet metal or other suitable material stamped or otherwise formed with forwardly projecting side walls 14a, 14b, 14c and 14d forming channels for receiving the abutting 15 end portions of the rails 10, 11, 12 and 13.

The side walls 14a and 14b extend along the outer edges of each corner member 14 and meet at the outer corner thereof. The walls 14c and 14d are disposed along the inner edge of the 20 corner member 14 terminating at the edge of a web 17 which extends across the angle of the L to form a support for the sheaves hereinafter described.

The numeral 14e denotes a flange which projects inwardly from the upper edge of each side wall 14a. The numeral 14f denotes a similar flange which projects inwardly from the upper edge of the wall 14b. The inner wall 14c is provided at the forward edge thereof with an outwardly disposed flange 14h and the wall 14d with an annular flange 14g. The flanges 14f, 14g, 14h and 14e are disposed in parallel relation to the main body of the corner member 14 and serve 25 to retain the frame members 10, 11, 12 and 13 30 in assembled relation.

The numeral 19 denotes a pin which is secured to the web 17 so as to project rearwardly therefrom at a right angle to the rear face of each corner member 14. Each pin 19 is provided with 40 two sheaves 20 and 21 which are operatively mounted thereon.

In assembling the frame, the ends of the rails 10, 11, 12 and 13 are positioned in the channels of the members 14 as illustrated in Figures 1 45 and 2. The corner members 14 provide efficient means for quickly and conveniently assembling the said frame members which will be securely held in position by the flexible elements 22 and 23 hereinafter described.

The numeral 22 denotes an endless, flexible belt 50 which is mounted in operative engagement with the sheaves 20 on each of the corner members 14. The flexible belt 22 is disposed along the rails 10 and 11 and extends from the sheave 20 at each 55

upper corner of the frame to the sheave 20 at the opposite lower corner thereof; the said flexible belt 22 thus crosses itself at the center of the frame. The numeral 24 denotes a coil spring 5 which is operatively interposed in the belt 22 to maintain the same in a stretched or taut condition.

The numeral 23 denotes a similar endless belt which is operatively mounted on the sheaves 21 10 at each corner of the frame to extend along the side portions 12 and 13. The belt 23 extends upwardly from the sheave 21 at each lower corner of the frame to the sheave 21 at the opposite upper corner thereof. The flexible belt 23 is likewise provided with a coil spring 25 which is operatively interposed therein to maintain the belt in a stretched condition. The forward faces of the rails 11 and 12 are offset rearwardly along the inner marginal portions thereof to provide 20 the longitudinally extending surfaces 11a and 12a which are disposed in a plane spaced rearwardly from the plane of the forward face of the frame.

The surfaces 11a and 12a may be provided with graduations or markings 26 and are each 25 provided with a longitudinally extending row of spaced curtain engaging pins 27. Each row of pins 27 extends in parallel, spaced relation to the inner edge of one of the rails 11 and 12.

The numeral 28 denotes a curtain engaging bar 30 which extends horizontally across the forward face of the frame with the end portions thereof overlapping the side rails 12 and 13. One end of the horizontal bar 28 is provided with a bracket 29 which secures the bar to the said rail 12 for 35 sliding movement longitudinally thereof. The bracket 29 projects rearwardly and is provided with a clamp 30 which is operable to secure the same to the portion of the belt 23 extending along the side rail 12. The rail 28 is provided adjacent the other end thereof with a block 31 which 40 is provided with a clamp 32 which is operable to fixedly secure the adjacent end of the bar 28 to the portion of the belt 23 extending along the rail 13.

The numeral 33 denotes a vertical curtain engaging bar which is provided at the lower end thereof with a bracket 34 which is in the form of a channel, in which is received the inner edge 45 of the rail 10 to slidably mount the same thereon.

The bracket 34 is provided with a clamp 35 which is similar to the clamps 30 and 32 and which is operable to secure the lower end of the bar 31 to the portion of the flexible element 22 extending along the rail 10. The vertical bar 50 extends upwardly with the upper end thereof engaging the inner portion of the marginal surface 11a. The vertical curtain engaging bar 33 is provided at the upper end thereof, on the rear face thereof with a bracket 36 which overlaps 55 the rear face of the rail 11 to slidably mount the same thereon.

The bracket 36 is provided with a clamp 37 for operatively securing the upper end of the vertical bar 33 to the portion of the flexible element 22 extending along the rail 11. The horizontal bar 28 is provided along the upper edge 60 of the forward face thereof with a rearwardly offset surface 28a and the vertical bar 33 is provided on the forward face with a similar surface 33a on the side presented toward the rail 12.

The surfaces 28a and 33a are similar to the surfaces 12a and 11a and each of said surfaces are likewise provided with the graduations 26 and the longitudinally extending row of pins 27.

It will be seen that each end of the curtain en-

gaging bar 28 is secured to portions of the flexible element 23 which are movable in the same direction and that a movement of one end of said bar will necessitate a similar movement of the other end thereof. Each end of the curtain engaging bar 33 is likewise secured to the portions of the flexible element 22 which are movable in the same direction. 5

With the frame positioned as shown in Figure 1, one edge of the curtain is secured to the pins 10 21 on the rail 11 and one end of the curtain is secured to the pins 27 on the rail 12. The bars 38 and 33 are then moved to the other edges of the curtain and the curtain is secured to the pins 27 on said movable bars. 15

In Figure 5 there is shown another method of mounting the flexible member 22 on the six sheaves 43a, 38, 39, 40, 41 and 42. The flexible member 23 is also shown operatively mounted on six sheaves 43, 44, 45, 46, 47 and 48. The opposite ends of the curtain engaging bar 32 is suitably secured to portions of the flexible member 22 and the opposite ends of the bar 33 are likewise secured to portions of the flexible member 33 which are movable in the same direction. Other 25 variations of this mounting shown may be used which will produce a like or similar result.

The brackets 29 and 36 are each provided with a locking arm 49 which is hingedly connected thereto and which is provided at the free end 30 thereof with an eye adapted to receive one of the pins 27 to lock the bars 28 in a fixed position. In the drawings there is shown a bracket 50 which is slidably mounted on the bar 33. The bracket 50 is provided with an ear 51 which projects over the lower portion of the forward face of the bar 28 and is provided with a thumb screw 52 which may be operated to lock the bars 28 and 35 together thus securing both of the bars against sliding movement in the frame. 40

While I have shown two specific forms of locking means for the bars 28 and 33, it is to be understood that any suitable locking means may be employed.

It will be seen that this invention provides a 45 frame which may be packed in a "knocked-down" condition to occupy a relatively small amount of space in shipment or storage and which can be quickly and conveniently assembled to provide a very efficient device for stretching curtains or other sheet material. 50

While the invention has been illustrated and described with reference to a particular frame, it is understood that any suitable frame may be employed or the sheaves 20 and 21 mounted on 55 a wall, floor or any suitable supporting structure.

It will also be understood that grommets, eyes, loops or any suitable mechanical equivalent may be employed in place of the sheaves 20 and 21. The flexible belts 22 and 23 may be in the form 60 of a cord, cable, wire, chain or any suitable flexible element which will suitably function as herein described.

Having thus illustrated my invention and described the same in detail, what I claim as new 65 and desire to secure by Letters Patent is:—

1. In a device of the character described, a rectangular frame having fixed sides, an endless belt mounted for operative movement thereon with portions of the belt extending along opposite sides movable in the same direction, a bar 70 extending across said frame in parallel relation to one side thereof, means to attach the ends of said bar to portions of said belt which are movable in the same direction and curtain en- 75

gaging means on said bar and the side of the frame disposed in parallel relation to the bar for securing a curtain therebetween.

2. In a device of the character described, a frame having fixed side rails, an endless belt, means to mount said belt for operative movement along opposite sides of said frame, a bar extending between opposite sides of said frame; means to slidably secure each end of said bar to the adjacent side rail of said frame and means to detachably secure the ends of said bar to the portions of said belt which are movable in the same direction; curtain engaging means on said bar and curtain engaging means on a side of said frame which extend in parallel relation to said bar.

3. In a device of the character described, a frame having fixed side rails; an endless belt, means to mount said belt for operative movement along opposite sides of said frame, a bar extending between opposite sides of said frame in parallel relation to the other sides thereof and means to secure the ends of said bar to the portions of said belt which are movable in the same direction, curtain engaging means on said bar and curtain engaging means on a side of said frame which is parallel to said bar.

4. In a device of the character described, a rectangular frame, having sheaves at each corner thereof, an endless belt operatively mounted on said sheaves with like movable portions of said belt extending along opposite sides of said frame, a bar extending across said frame with the ends thereof secured to the like movable portions of said belt, curtain engaging means on said bar and curtain engaging means on the side of the frame positioned opposite said bar.

5. In a stretching device, a support, an endless belt operatively mounted thereon with like movable portions thereof extending along opposite sides of said support, and a curtain engaging bar extending between and secured to said like movable portions of said belt and curtain en-

gaging means along the side of said support positioned opposite said bar.

6. In a stretching device, a support, an endless belt operatively mounted thereon with like movable portions thereof disposed along opposite sides thereof, a curtain engaging bar extending between said like movable portions and operatively secured thereto so as to be movable therebetween and a second belt operatively mounted on said support with like movable portions thereof disposed along the other two sides thereof, a second curtain engaging bar extending between and secured to said like movable portions of said second belt.

7. In a stretching device, a collapsible rectangular frame, curtain engaging means extending along two adjacent sides thereof, two curtain engaging bars slidably mounted on said frame, said bars disposed at a right angle to each other with each bar opposite one of the sides of said frame which is provided with said curtain engaging means and an endless belt connecting the opposite ends of each bar to restrict the end portions thereof to a like movement and maintain said bars at a right angle to the adjacent portions of said frame.

8. In a stretching device, a supporting structure comprising side rails and end rails, corner members having sockets for receiving the end portions of said rails, said corner members adapted to position said rails in the form of a rectangular frame, sheaves on each corner member, a flexible belt holding said rails in an operative position in said corner members, said belt mounted on said sheaves with like movable portions thereof extending along opposite sides of said frame, a bar extending across said frame with each end thereof connected to one of said like movable portions, means on said bar and on said frame for engaging the article to be stretched.

ARTHUR G. BORNTRAEGER.
